ABSTRACT: A vacuum system comprising a two-phase pumping arrangement that is connected over a main conduit to a remotely disposed evacuation system. The main conduit is normally closed-off during the first phase of evacuation by a plunger associated with an electrical solenoid. A screened detour conduit is provided around the blocked main conduit. Thereby, the first pump phase evacuates air from the article over the screened detour path, filtering out unwanted particles that are collected in a trap well positioned adjacent the screen area. The second and final phase of evacuation is initiated after the solenoid is energized to remove the block from the main conduit.

VACUUM SYSTEM

BACKGROUND OF THE INVENTION

1. Field of the Invention

This invention is directed to hydraulic vacuum systems but more specifically to vacuum pumps where an article fitted to the pumping system can be evacuated from an atmospheric condition to a given vacuum. Normally, a device of this type employs a series of pumps that provide a rough and fine pumping combination to achieve a desired vacuum of an article.

2. Description of the Prior Art

Articles of work that require evacuation such as bell jars, lamp envelopes, etc. are normally attached directly to a central orifice of a pumping system. A series of interconnected mechanical and diffusion pumps are then operated to evacuate gas from the article to a desired vacuum. Usually a first pumping-down called a "purge" or "rough-pump" is accomplished by a mechanical pump. This initial surge of evacuated currents frequently sweeps or cleans out any sediment or residue left in the article from a previous step of fabrication. The sediment is drawn from the article to an evacuation port by way of the internal mechanism of the pump. The particles collect within the pump mechanism which necessitates frequent repairs. Also, constant ingestion of these particles can necessitate early replacement of the pump. Even with expensive practices such as air cleaning of the article prior to evacuation failed to reduce the costly downtime and early replacement of the pump.

SUMMARY OF THE INVENTION

In our invention we have overcome these problems by designing a built-in sediment trap fully operative during the first purge cycle of the evacuation of the article.

During the first cycle, a new route from the article to pump is established by blocking the main route. This new route is provided with a screened trap that prevents residue and sediment from reaching the pump. This purge cycle is of short duration and at its termination automatically actuates a fine pumping or diffusion pump cycle.

Just prior to initiation of the fine pumping cycle, the block is removed from the main route. This allows a direct, un-screened path from the article to the pump providing high speed evacuation of the article.

This unique system provides a trouble-free cleansing arrangement of an article for an unlimited usage in vacuum systems.

These and other objects, features and advantages of the invention will be apparent from the following specification when taken in conjunction with the accompanying drawing.

BRIEF DESCRIPTION OF THE DRAWING

The drawing is a schematic view of an evacuation system showing in particular the article and pumping source and the interconnected piping therebetween.

DESCRIPTION OF THE PREFERRED EMBODIMENT

Referring to the drawing, our embodiment of a sediment trap comprises a piping system of standard tubular configuration. The pumping system generates from a main pumping source 10 to an article manifold 12. In a specific example we describe and illustrate a leak detector apparatus showing how a sediment of our design would function.

In a leak detector operation, series of pumps are utilized for attaining a desired vacuum within an article. The two pumps most commonly used are a standard mechanical pump and a diffusion pump. In the first phase of pumping the mechanical pump is initiated to introduce a pumping cycle where the interior of the article 14 affixed to the manifold 12, is evacuated from an atmospheric condition to about 10 microns of vacuum. Thereafter the diffusion pump is actuated to evacuate the article to about 10^{-4} microns of vacuum.

On the initial surging cycle, the evacuation of air and/or other gases from the article 14 collects residue or particles left from a previous operation and carries this sediment back to the pumping source 10.

To prevent this sediment from reaching the intricate pumping mechanism we detour the main straight route from article to pump. The complete tubular piping system can be clearly seen in the illustration of the drawing where a straight main pipe 16 having one end affixed to the pumping source 10 and the other end fitted with a short upturned run 18. An article manifold adjustable fitting 12 is positioned thereto, with a conventional knurled closure ring 20 capable of being rotated to receive and hold an article.

The main pipe 16 is provided with two spaced apart short-run legs 22 and 24 extending down from the pipe 16. The legs 22 and 24 mate with coinciding short legs 28 and 30 of a sediment trap 26. The legs 28 and 30 are extensions of a straight run 32.

The legs 22 and 24 are joined to the legs 28 and 30 by standard compression rings 34 and 36. The joining of legs 22 and 24 to legs 28 and 30 must be attained with complete air tight joints and is accomplished by using compressible gaskets between the joined ends. In the fitting of leg 24 to leg 30, a simple λ O-ring gasket 38 is placed between the ends and then compression ring 36 is affixed to completely seal this joint.

The joining of legs 22 and 28 are done in a similar manner with the exception that a screen 40 is spaced between two O-ring gaskets 42 and then the compression ring 34 is secured thereto.

A lower extending leg 44 in register with leg 28 defines a sediment well 46 which is provided with a removable screw cap 48.

To complete the device, a solenoid 50 having a coil 51 is fitted to the top area of the main pipe 16. The solenoid is provided with an internal blocking plate 52 fitted within guideways 54 of the pipe 16 and guide between the coil 51 of the solenoid 50. Normally, the blocking plate 52 is spring urged in the opening of pipe 16 by a spring 56.

A complete sequence of an evacuation of an article will now be described. An article 14 is fitted into the manifold 12 by rotation of the knurled closing ring 20. Articles of different configuration can be accepted by interchangeable manifold fittings. As mentioned previously, the pumping source is initiated with a purge flush accomplished by a mechanical pump. It may be noted at this time that the main pipe 16 is closed by block 52. Therefore air evacuated from the vessel or article 14 is drawn over the detour path, designated in the drawing by the broken arrows. This first rush of air carrying any particles of residue follows the bypass piping 24, 30, 32 and 28 where the particles are trapped by the screen 40, positioned between legs 22 and 28. The filtered air continues through the screen and completes its circuit back to the pumping source 10.

At this particular time the operation, the mechanical pump is isolated from the system and a diffusion pump, a part of the pumping source 10, is put into operation. Just prior to the operation of the diffusion pump the solenoid 50 is activated thereby removing the block by means of energizing the coil 51.

As mentioned previously, the diffusion pump accomplishes the desired vacuum of the article in this case a vacuum in the vicinity of 10^{-4} microns. With the block 52 removed from the main pipe 16 a direct run from article to pump is established where residue clear air is rapidly drawn back to the pumping source 10. After the article has been evacuated to the desired vacuum, the analysis of the part being evacuated is made, then the part and system is put back to atmosphere. A new article can be fitted to the manifold and the operation is repeated.

During isolation shutdown of the pumps, and during attachment of a new article to the manifold any sediment caught on the screen will fall into the sediment trap 46. After many repeated operations as described above the sediment in the trap can be easily removed by unscrewing the cover 48.

An added precaution to catch and retain minute sediment particles in the trap area is accomplished by coating the inner walls of the trap area with a low vapor pressure grit catching grease. When this grease is used the complete trap piping has to be taken off and cleaned, this is accomplished by removing the compression rings 34 and 36. The trap operates normally without the grease, but if added protection is required, this can be utilized.

It is apparent that modifications and changes can be made within the spirit and scope of the instant invention, but it is our intensions, however, only to be limited by the appended claims.

We claim:

1. A vacuum pumping system comprising:
a pumping source including a mechanical pump and a diffusion pump;
a main evacuation line directed from said pumping source;
an article receiver positioned on said main evacuation line;
a removable blocking means positioned in said main evacuation line between said article receiver and said pump;
a detour path connected to said main evacuation line and

arranged so that said blocking means can be bypassed;
filter means fitted within said detour path;
gases from the article to be evacuated being directed through said detour path and hence said filter when the mechanical pump is actuated and thence being directed through said main evacuation line when said diffusion pump is actuated, whereby extraneous particles are filtered from the gases and prevented from entering the pumping source when said mechanical pump is actuated.

10 2. The vacuum pumping system according to claim 1 wherein said filter means includes a removable capped well, whereby particles caught in the screen are collected therein.

15 3. The vacuum system according to claim 1 wherein said blocking means comprises an electrical solenoid having a plunger defined as a block, said plunger normally spring urged to block said main evacuation line and when energization of said solenoid thereby removes said plunger from said main evacuation line after said rough pumping cycle is completed.

20 4. The vacuum system according to claim 1 wherein said filter means is a screen.
